ELECTRIC LAMP UNIT

Harry A. Douglas, Bronson, Mich., assignor to
Kingston Products Corporation, a corporation
of Indiana

Application February 26, 1935, Serial No. 8,312

7 Claims. (Cl. 240—41)

My invention relates to electric lamp units, and more particularly to electric lamp units comprising an incandescent electric lamp mounted in a reflector, as in an automobile headlight, and the 5 principal object of my invention is to provide a new and improved unit of this type.

In the drawings accompanying this specification, and forming a part of this application, I have shown, for purposes of illustration one form 10 which my invention may assume. In these drawings:

Figure 1 is a vertical sectional view, certain parts being fragmentarily shown, of one embodiment of my invention.

15 Figure 2 is an end elevation of a socket unit forming part of the embodiment of Figure 1.

Figure 3 is a plan view of the parts shown in Figure 2, looking in the direction of the arrows, on the line 3—3, the parts in Figure 3 being 20 shown before they are completely assembled.

Figure 4 is a developmental view, on a smaller scale, of a sheet metal punching which may be used to form a portion of the socket unit.

Figure 5 is a front elevation of a detail of the 25 socket unit.

Figure 6 is a side elevation of the socket unit completely assembled.

Figure 7 is a front elevation of the socket unit completely assembled.

30 Figure 8 is a front elevation of a portion of a reflector.

Figure 9 is a front elevation of the reflector shown in Figure 8, with the socket unit shown in Figure 7 assembled therewith.

35 Figure 10 is a transverse sectional view of an electric incandescent lamp adapted to be used with the present embodiment of the invention.

Figure 11 is a section taken on the line 11—11 of Figure 1, looking in the direction of the 40 arrows, and

Figure 12 is a fragmentary detail sectional view taken along the line 12—12 of Figure 11, looking in the direction of the arrows.

Referring to Figure 1, the embodiment of my 45 invention here illustrated is shown as including an incandescent electric lamp 20 adapted to be suitably connected to a reflector 21, the reflector being shown fragmentarily. The lamp 20 is provided with a base 22, which in this instance includes laterally extending positioning means 23 also forming part of the means for connecting the lamp to the reflector. The laterally extending portion 23 of the base comprises a collar 24 surrounding the base, and a radially extending 50 flange 25 on the collar 24. The collar 24 may be

fastened to the base 22 in any suitable manner, as by soldering 26 (see Figure 10).

The collar 24 is here shown as adapted to be received loosely through an aperture 27 in the reflector. In this instance the aperture 27 is formed in a flange 28 extending radially inwardly from a tubular portion 29 forming a rearward extension on the reflector 21.

In order to definitely position the lamp 20 with respect to the reflector, the flange 25 may be 10 provided with circumferentially spaced indentations 30, 31, 32, (see also Figure 10), forming axially extending projections, only one of which 33 is visible in Figure 1. The projections, such as 33, are adapted to abut the front face of the 15 flange 28. The words front and rear will be used to designate respectively those portions of a part in question which are nearest to the light source of the lamp 20 and those that are furthest from it. The projections, such as 33, are desirably three in number so that when the plane of the ends of these projections is in registry with the plane defining the surface of the flange 28, the plane of the positioning flange 25 with respect to the reflector will be definitely determined. The periphery of the flange 25 is here 20 shown as spaced slightly from the inner periphery of the tubular portion 29, but these parts may be 25 made to gauge each other, that is, fit snugly.

Adapted to cooperate with the lamp 20 is a 30 socket unit 34 comprising a shell 35 desirably of generally cylindrical form and desirably formed of sheet metal. The shell 35 is in this instance provided with a plurality of integral connector portions 36, 37, 38, unequally spaced circumferentially, extending in a direction generally parallel to the axis of the socket. Each of the portions 36, 37, 38 includes an axial portion 39, radially off-set from the shell 35, connected by a radial portion 40 with the shell 35. The radial portion 40 35 is in this instance reduced in circumferential width with reference to the axial portion 39, the reduction in width extending from the radial portion 40 somewhat into the axial portion 39, so that the shoulders 41 are formed.

The ends of the connector portions 36, 37, 38 45 are formed in the shape of hooks having their throat portions defined by the edges 42, 43 of the axially extending portions 39. Only one of the hooks, that which is formed on the connector portion 36, will be described in detail, inasmuch as the hooks formed on the portions 37, 38 are identical therewith. The hook has a mouth 44, the sides of which, extending to the bottom thereof, are defined by converging lines 45, 46, forming 50

a generally V-shaped recess, the bottom of which may be rounded off as indicated. The end of the throat portion of the hook may be beveled off as at 41. The outer edge of the lip of the hook is defined by an axial line 48 and that portion of the lip of the hook merging with the inside of the mouth of the hook may be beveled off as at 49, so that the apex 108 of the lip is formed by the lines 46 and 49. The free end of the hook is defined by a line 50 in a plane transverse to the axis of the socket unit.

The socket unit is provided with an insulating contact carrier 51, of an outside diameter equal to the inside diameter of the shell 35, and having a plurality of projections, which may be three in number, two of which 52 and 53 are visible in Figure 3. The plurality of projections, such as 52, 53, are desirably unequally spaced and of different circumferential width, and are adapted to be received in a plurality of complementary recesses 54, 55, 56 in the rear edge of the shell 35. Spaced at desirable places around the periphery of the rear edge of the shell 35 and extending generally axially therefrom are a plurality of projections or fingers 57, which may be clinched radially inwardly over the rear face of the insulating carrier 51 to thereby hold the carrier assembled with the shell 35.

The contact carrier 51 is adapted to carry contacts 59, 60, these contacts being desirably formed as enlarged heads on shanks fitted over and swedged to the ends of conductors 61, 62 respectively. The conductors are disposed in sleeves 63, 64, the sleeves being slidable within bushings 65, 66, which are fixedly mounted, in any suitable manner, as by beading, through the insulating carrier 51. Springs 67, 68 surround the sleeves 63, 64 between the bushings 65, 66 and flanges on the inner ends of the sleeves 63, 64 abutting the contacts 59, 60.

The contacts 59, 60 are adapted to make contact respectively with a pair of contacts on the base 22 of the incandescent lamp. One of the contacts 69 on the base of the lamp is shown in Figure 1 as in contact with the socket contact 69. The provision of the plurality of contacts on the lamp base enables the use of a multiple filament lamp, the lamp 20 being here shown as provided with two filaments 70, 71, one of which 70 may desirably have its lighting center at some predetermined point with respect to the reflector, as for example the focus, and the other of which 71 may be displaced from the filament 70 and may be used for providing dim light or so-called tilted light. The filaments 70, 71 have their terminals connected in a well known manner to the lamp base 22 and to the contacts on the lamp base. The passage of current through either one or both of the filaments 70, 71 may be controlled in any suitable manner by switching means (not shown) interposed in the conductors 61, 62.

The socket unit 34 also includes a biasing means 72, in this instance comprising a ring 73 of sheet metal, provided with portions, circumferentially unequally spaced, extending in a generally radial direction outwardly from the ring 73, and looped or bent radially inwardly so as to form the spring loops 74, 75, 76. The free ends 77 of the spring loops may be reduced in width, and are adapted to be received respectively in a plurality of apertures 78, 79, 80 formed in the shell 35. The apertures 78, 79, 80 are here shown of trapezoidal form, with the sides of the trapezoid tapering toward the rear of the

socket unit, and are unequally spaced to accommodate the unequal spacing of the spring loops.

The ring 73 has its central aperture 109 desirably of the same diameter at the aperture 27 in the reflector, and is provided with a plurality of auxiliary apertures 81, 82, 83. These apertures desirably form radial extensions of the central aperture of the ring, and as they are identical, but one of them 81 will be specifically described. The aperture 81 comprises a radially extending portion 84, which is of a circumferential width sufficient to pass over the reduced radial portion 40 of the connector portion 36. The radial outer end of the aperture 81 is undercut so as to form a circumferentially wider portion 85. The radial outer peripheries of the undercut portions 85 are desirably arcuate and concentric with the aperture 109. The undercut portion 85 is of sufficient circumferential width to pass over the axially extending neck 39 of the connector portion 36. The apertures 82, 83 are formed and spaced so as to cooperate with the connector portions 37, 38 respectively, in a manner similar to that described in connection with the aperture 81 and the connector portion 36.

The ring 73 is provided with a plurality of frontwardly extending detents, here shown as three in number 86, 87, 88. These detents may be formed by striking up the metal of the ring 73, adjacent the clockwise side of the undercut portions 85 of the apertures 81, 82, 83.

Referring to Figure 8, the reflector 21 is here shown as having the flange 28 provided with three apertures 89, 90, 91, disposed concentrically about the aperture 27, and adapted to receive the connector portions 36, 37, 38. These three apertures are all identical and therefore but one of them, the aperture 89, will be described. The aperture 89 has its radial outer and inner edges defined by arcuate portions, the arcs being concentric with the aperture 27. In this instance the aperture 89 is not formed as an extension of the aperture 27, but is separately formed. The aperture 89 comprises two portions, one of which 92 is narrower radially than the other 93.

The apertures 92 and 93 merge into each other, and the circumferential ends of the apertures 93, 92 are defined respectively by radial lines 94, 95.

The lateral extension 25 on the lamp base is provided with apertures 96, 97, 98, in this instance three in number, adapted to receive the connector portions 36, 37, 38. Each aperture comprises a set of two apertures, and since all of the apertures are identical but one of them, 96, will be described. The aperture 96 comprises a large portion 99 and a smaller portion 100, these portions being in this instance separate from each other. Both the aperture 99 and the aperture 100 have a radially outer edge and a radially inner edge, defined by arcs concentric with the lamp base and of the same or substantially the same radii as the outer and inner peripheries of the arcuate axially extending portions of the connector portions 36, 37, 38. The circumferential ends of the aperture 99 are defined by radial lines 101, 102, while the circumferential ends of the aperture 100 are defined by radial lines 103, 104. The lines 101 and 103 form between them a generally radially extending portion 105, which is of such circumferential width as to be receivable within the mouth 44 of the hook portion 36. Thus, the edges 101 and 103 are adapted to engage the V-shaped recess formed by the edges 45, 46 of the bottom of the mouth 75

of the hook. The aperturings 97, 98, in a manner described in connection with the aperturing 96, also form radially extending portions 106, 107 adapted to cooperate with the hooks of the connector portions 37, 38 in a manner similar to that described in connection with the radially extending portion 105 and the hook of the connector portion 36.

In the event that it is desired to manufacture the socket unit out of sheet material, a blank, such as illustrated in Figure 4, is first stamped out and shaped to the form shown in Figures 2 and 3, where the portion 35 forms a cylindrical shell and the integral connector portions 36, 37,

15 38 are shaped so that the axially extending portions 39 along with the hook-shaped ends thereof are of arcuate cross-section, the arcs being of the same radius, and concentric with the axis of the shell 35.

20 The contact carrier is then inserted into the shell 35, with the projections 52, 53 in the recess 54, 55 in the end of the shell, the projection, corresponding to the projections 52, 53, not visible in Figure 3, being received in the recess 56 in the 25 end of the shell. The fingers 57 are then clinched over the rear end of the contact carrier 51.

The ring 73 of the biasing means may be slipped, from the rear, over the connector portions 36, 37, 38, the narrow portion 84 of the apertures 81, 82, 30 83 passing freely past the reduced portions 40 of the connector portions 36, 37, 38, and the undercut portions 85 of the apertures 81, 82, 83 passing freely along and receiving within them the neck portions 39 of the connector portions 36, 37, 38. 35 The ring 73 is moved towards the ends of the connector portions until the front face of the ring 73 abuts the apexes 108 of the lips of the hooks. The spring loops 74, 75, 76 are then flexed so that the respective free ends 77 thereof are 40 brought into registry with the openings 78, 79, 80 in the shell 35. The free ends 77 may then be directed radially inwardly into the openings 78, 79, 80 in the shell 35, taking the position illustrated in Figures 1 and 6, in which the ends 77 underlie the inner periphery of the shell. The 45 assembled socket unit then has the appearance, in side elevation, as illustrated in Figure 6, and in front elevation as illustrated in Figure 7.

The socket unit may now be connected to a reflector by inserting the ends of the hooks of the connector portions 36, 37, 38 into the apertures 89, 90, 91 in the reflector. The ring 73 then abuts, and more particularly the forwardly extending detents 86, 87, 88 abut the rear of the flange 28 of the reflector. The circumferential width of the hooks between the outer axial edges 42, 48 thereof, is greater than the circumferential width of the respective apertures 89, 90, 91. Hence as the hooks are inserted in those apertures the beveled edges 47 of the ends of the throats of the hooks will engage the respective radial edges 94 of those apertures. By turning the socket unit 34 bodily in a direction such that the beveled portions 49 of the hook lips engage the radial edges 95 of the apertures 89, 90, 91 respectively, the resulting cam action between those beveled edges and the radial edges 95 pulls the connector portions 36, 37, 38 further through the reflector apertures, against the increased bias of the biasing means 72, until the apexes 108 of the lip portions of the hooks ride onto the front surface of the flange 28. Sufficient rotational movement of the socket unit in the same direction causes the detents 86, 87, 88 to snap 75 into the portions 93 of the apertures 89, 90, 91

respectively, the trailing edges of the detents then being opposed to the radial edges 94 of the detent-receiving aperture portions 93. The action of the biasing means 72 holds the detents 86, 87, 88 in place and hence prevents unintended disengagement of the socket unit from the reflector. The parts are then in the position shown in Figure 9 in which the reflector, with the socket unit assembled therewith, is viewed from the front. The fit of the arcuate connector portions 10 36, 37, 38 in the arcuate apertures 89, 90, 91 may be snug enough to gauge or locate the connector portions with respect to the reflector.

If it is now desired to mount with the reflector a lamp, such as the lamp 20 of Figure 1, the larger portions 99 of the aperturings 96, 97, 98 are brought into registry with the ends of the hooks of the connector portions 36, 37, 38. The lamp is moved toward the reflector against the bias of the spring-pressed contacts 59, 60, until 20 the projections, such as 33, corresponding to the indentations 30, 31, 32 abut the front surface of the flange 28. If the lamp is then turned in a clockwise direction, as viewed from the front of the reflector, the edges 101 of the aperture portions 99 of the aperturings 96, 97, 98 will engage 25 respectively the beveled portions 49 of the hook lips and by cam action will pull the connector portions 36, 37, 38 further through the reflector against the bias of the biasing means 72. Continuation of the clockwise rotation of the lamp will cause the apexes 108 of the lips of the hooks to ride over the front face of the radially extending portions 105, 106, 107 and then the apexes 108 of the hook lips will snap respectively into 30 the smaller aperture portions 100 of the aperturings 96, 97, 98. The hooks now have the position illustrated in Figure 12. Here only the connector portion 36 is shown, but all of the connector portions assume a similar position. In that position the sides 45, 46 of the hook mouth straddle the radial portion 105, of the lamp base flange 25, those sides being in contact with the edges 101 and 103 respectively of the radial portion 105. The biasing means 72 of course presses the flange 45 40 toward the front face of the reflector, and hence presses the projections 33, corresponding to the indentations 30, 31, 32 into abutment with the front of the reflector flange 28. Since these projections are in radial alignment with the radial portions 105, 106, 107 against which pressure is applied to bring the flange 25 into registry with the reflector, distortion of the flange 25 by that pressure is avoided.

The lamp may be assembled with the positioning means 23 by placing the positioning means on a standard with the lamp base within the collar 24 and then adjusting the lamp until the lighting center of the desired filament thereof is in a predetermined position, whereupon the collar 24 is soldered to the lamp base. The position of other filaments of the lamp may be likewise predetermined.

It will be evident from the foregoing that my invention provides a means whereby a lamp may be connected to a reflector with the lighting center of a filament thereof at a predetermined point with respect to the reflector, and also that the position of the lamp about its axis will be predetermined so that the proper contacts thereon will be brought into engagement with contacts on a socket unit which in turn has the position of its contacts about the axis of the socket predetermined with respect to the reflector.

When it is desired to disconnect a lamp from 75

the reflector, the lamp is turned counter-clockwise as viewed in Figure 11, whereby the edges 103 of the radial portions 105, 106, 107, by cam action against the sides 46 of the hook mouths, 5 force the connector portions 36, 37, 38 frontwardly, against the bias of the biasing means 72, thereby permitting disengagement of the lamp, as will be evident.

The socket unit may be disconnected from the reflector either by moving the ring 13 away from the flange 28, to disengage the detents 86, 87, 10 88 from the aperture portions 93 of the apertures 89, 90, 91, or by first disengaging the ends 71 of the spring loops 14, 15, 16 from the apertures 78, 79, 80, whereupon the entire biasing means 72 may be slipped rearwardly off of the connector portions 36, 37, 38. In either case the socket may then be turned so as to disengage the hooks on the connector portions 36, 37, 38 from 15 the apertures 89, 90, 91.

In view of the foregoing it will be apparent to those skilled in the art that the herein disclosed embodiment of my invention provides a new and improved incandescent electric lamp unit, and 20 accordingly accomplishes at least the principal object of my invention.

It will also be obvious to those skilled in the art that my invention may be embodied in other constructions wherein the reflector, or other 25 mounting for the lamp, the socket unit, and the lamp and its base, may assume a variety of forms, variously changed and modified within the spirit of the invention.

In general it will be obvious to those skilled 30 in the art that the features of my invention may be individually changed and modified, without departing from the spirit of my invention or sacrificing all of the advantages thereof, and accordingly that the disclosure herein is illustrative 35 only, and that my invention is not limited thereto.

I claim:

1. A holding unit, for cooperation with an incandescent electric lamp, adapted to be connected to a mounting, comprising: a socket body, said body having circumferentially spaced connector portions having lateral extensions; a member adapted to abut said lateral extensions; resilient means for biasing said member toward said lateral extensions; said resilient means having a free end directed toward said socket body; and said socket body having an opening in its periphery for receiving said free end, said free end reacting against a margin of said opening.
2. A holding unit, for cooperation with an incandescent electric lamp, adapted to be connected to a mounting, comprising: a socket body, said

body having connector portions having lateral extensions; a member adapted to abut said lateral extensions, said member having a first aperture, and compound auxiliary apertures disposed about said first aperture, said auxiliary apertures forming radial extensions of said aperture, said compound apertures each comprising a first portion through which one of said connector portions extends and a narrower portion joining said first portion and said first aperture. 10

3. An incandescent electric lamp, having a base provided with a lateral extension, said lateral extension being provided with a plurality of circumferentially spaced sets of apertures, each set including two separate circumferentially spaced apertures. 15

4. In combination: a mounting, having a plurality of apertures; an incandescent electric lamp, having a base; a lateral extension on said base provided with a plurality of circumferentially spaced sets of apertures, each set including two separate circumferentially spaced apertures; a holding unit for said lamp, having portions disposed through said mounting apertures and through one aperture of each of said sets of apertures respectively; and said portions of said holding unit having parts overlying said lateral extension between said separate apertures and extending into the other apertures of each of said sets of apertures respectively. 20

5. An incandescent electric lamp, having a base provided with a lateral extension; said lateral extension being provided with a plurality of circumferentially spaced sets of apertures, each set including two separate circumferentially spaced apertures; and projections on a face of said lateral extension extending in the general direction of the axis of said lamp and disposed in substantial radial alignment with the spaces between said separate apertures respectively. 25

6. An incandescent electric lamp, having a base provided with a lateral extension; said lateral extension being provided with a plurality of circumferentially spaced sets of apertures, each set including two separate circumferentially spaced apertures one of which is of materially greater circumferential extent than the other. 30

7. An incandescent electric lamp, having a base provided with a lateral extension; said lateral extension being provided with a plurality of circumferentially spaced sets of apertures, each set including two separate circumferentially spaced apertures, at least one of said separate apertures of each of said sets having radially outer and inner peripheries defining radially spaced arcs 35 concentric with the axis of said lamp. 50

HARRY A. DOUGLAS.
